Stone and Stone
ATTORNEYS

UNITED STATES PATENT OFFICE.

GEORGE C. FATSCHER, OF NEW HAVEN, CONNECTICUT, ASSIGNOR TO THE NEW HAVEN SAND BLAST COMPANY, OF NEW HAVEN, CONNECTICUT, A CORPORATION OF CONNECTICUT.

DUST ARRESTER.

Application filed October 23, 1923. Serial No. 670,327.

To all whom it may concern:

Be it known that I, GEORGE C. FATSCHER, a citizen of the United States of America, residing at New Haven, in the county of 5 New Haven and State of Connecticut, have invented certain new and useful Improvements in Dust Arresters, of which the following is a specification.

My invention relates to dust arresters, 10 and particularly to apparatus for removing from an exhaust draft the entrained dust particles. The present invention presents certain improvements in construction and operation over those of my prior Patent No. 15 1,316,883, September 23, 1919, as will be hereinafter described or made clear by the accompanying drawings, in which—

Fig. 1 is a vertical section through an ar- 20 rester in which my improvements are em- bodied in one form;

Fig. 2 is a section on the line 2—2, Fig. 1; Fig. 3 is a broken plan view of Fig. 1;

Fig. 4 is an enlarged, broken, vertical section illustrating the filter bag construction 25 and mounting; and

Fig. 5 is an inverted plan of the bottom bag frame showing my improved anchorage for the bag mouths and a filler block.

The arrester comprises an air-tight steel 30 housing 15 divided into inlet and exhaust chambers, 16 and 17 respectively, by a wooden partition and stationary bag frame 18 which extends across the lower portion of the housing and is bolted to side and in- 35 termediate angle irons 19. An inlet port 20 opens to the chamber 16 below the partition and is adapted for connection to the inlet duct 21. An outlet port 22, at the upper portion of the chamber 17, opens to the exhaust duct 23, which leads to an exhaust fan (not shown). The bottom of the inlet chamber is shaped to form one or more hoppers 24 which receive the dust caught by the arrester bags and subsequently dis- 45 charged to the hoppers.

The partition 18 is provided with a series 50 of parallel slots 25, into which project the lower and open ends of the filter bags 26. The mouths of the bags are secured in rab- berts 27 formed along the lower margins of the slots 25. As a simple and effective hold- ing means, I provide for each opening a pair 55 of wire rods 28 each offset at one end 29, the

length of the rods 28 substantially corre- 55 sponding to the length of the slots 25, and the offset ends 29 substantially corresponding to the width of the slots 25. The ar- 60 rangement of the rods in adjusted position with their offset ends 29 at the opposite ends of the slot 25, is shown in Fig. 5. A con- tinuous loop to accommodate the rods is 65 formed at the bag mouth, by stitching down the turned over edge of the fabric, and open- 70 ing holes in the outer wall of the loop to permit entry of the rods. After the rods 75 have been thus inserted they are forced into the rabbets 27, in which position they are securely clamped by hooked clips 30 screwed or nailed to the frame 18 at appropriate points along the length of the slots 25 and 70 at the ends thereof. It will be noted that the rods 28, with their offset ends 29, form in effect a rectangular frame substantially 75 corresponding in area with the slot 25. Under proper conditions a one-piece stretching frame may be used at the mouth of the bag, but I prefer the two-piece construction shown since it not only accommodates itself to variations in size of the opening 25, and to slight variations in dimension of the bag, 80 but it also insures firmer clamping in the rabbets 27 by the clips 30, and thus a stronger grip on the fabric. Their effect, in any case, is to hold the mouth of the bag open and to 85 anchor it firmly at the openings in the fixed frame 18.

The upper or closed end of the bag is sup- 90 ported by rods 31 engaged in loops 32 formed in the manner described in my patent above mentioned. The rods 31 are engaged by 95 clamps 33 with associated bolts 34 attached to the bars 35 extending transversely of the bag group and constituting portion of the floating, top-suspension frame. The con- 100 struction of the floating frame varies with 105 the number of bags in each frame group. As shown there are two bars 35 for each bag group, united by an intermediate and cen- trally located cross bar 36. The frame has 110 a floating suspension through springs 37 from angle irons 38 on the roof of the hous- 115 ing 15. Centrally arranged on the cross bar 36 is mounted a pneumatic vibrator 39 provided with a connection 40 for attach- 120 ment thereto of a flexible pneumatic pres- 125 sure hose (indicated in dotted lines, Fig.

1). The details of construction of the vibrator 39 are not shown inasmuch as they constitute no part of my invention per se. It suffices to state that it comprises a relatively heavy slug which, when in operation, imparts hammer blows alternatively to the opposite ends of the casing 39. (See patent to Pickop No. 1,336,921.)

It will be noted that the suspension frame 10 and associated suspension springs afford a floating bag support which carries, as a unitary, self-contained element, the vibrator 39. The importance of this structure will be appreciated when it is considered that the dust gathered by the bags in the course of several hours run, without cleaning, is frequently so heavy as to cause the springs to elongate and thus let the suspension frame down so far that the usual shaking cams 20 fail to operate, or act inefficiently. The present vibrator, mounted directly on the suspension frame, follows the latter as it sinks and operates with perfect efficiency regardless of the added weight of the dust 25 accumulation in the bags.

Extending between the bag frame 18 and the top supporting rods 31, are diagonally arranged beater wires 41 lying against the opposite faces of the bags 26 and preferably 30 provided intermediate their length with springs 42.

In order to prevent bellying of the body 25 of the bags under the suction of the exhaust, and the consequent danger of contact between the sides of adjacent bags, I stitch the sides of each bag together by vertical courses 43, thus forming in effect a series of vertical channels extending from a point 40 slightly spaced from the intake mouth of the bag to a point spaced from the upper portion of the bag.

In order to obtain access to the interior 45 of the dust chamber for inspection and pair, I provide appropriate door openings 45 and 46 to the interior of the casing. I also provide filler blocks 47 which may be temporarily inserted in the partition openings 25 to plug the latter, should it become necessary to cut out a defective bag. The 50 operation of the arrester may then be continued without further interruption.

The action of the dust arrester is as follows. When the exhaust fan is started the air is drawn through pipe 23 from chamber 17 and into the latter through the bags 26 from the chamber 16, to which the inlet port 20 opens. Upon the entrance of air into the relative quiet of chamber 16, the heavier entrained particles fall into the hoppers 24, while the lighter particles are carried with the air through the openings 25 in the bag frame 18 to the interior of the bags 26. The particles are caught by the latter, while the clean air passes through 60 the bags to the chamber 17 and thence to 65

the exhaust fan, which either discharges the air or returns it to the chamber whence it was derived, through the pipe 21. When the exhaust fan is operating, the bags 26 are maintained quiet. When it is desired to 70 clean them, the exhaust fan is stopped, and air under pressure is admitted to the pneumatic impact device 39. The slug therein is at once reciprocated and imparts a series of sharp impact blows in opposite directions to 75 the suspension frame 35—36. Inasmuch as the latter is hung on the springs 37, each downward impact of the slug drives the suspension frame downward, thus relaxing the tension 26 upon the bag fabric and placing the springs 37 under additional stress. Immediately following the downward stroke, the plunger is thrown upward by the pneumatic pressure. As it rises, the springs 37 contract and again tension the bags 26 with a snap action, which effect is augmented by the upward impact of the pneumatic slug against the top of its casing 38. The combined action of the impact plunger 80 and the springs, which alternately slack 85 and snap the bag fabric, very effectively frees the adherent dust particles therefrom. The dust falls down through the open bottoms of the bags into the hoppers 24, thus leaving the bags clean and ready to 90 efficiently perform their function when the exhaust fan is again set in operation.

The freeing of the dust particles from the bag fabric is augmented by the beater wires 41, which, during the vibration of the 100 suspension frame 35—36, are alternatively slackened and tightened, and thus beat the outer faces of the bags and help to loosen the dust particles from the bag walls.

The improvements above set forth greatly 105 increase the efficiency of the apparatus of my prior patent, and I claim as my invention—

1. In a dust arrester, a closed casing, a fixed partition subdividing the interior of 110 said casing into upper and lower chambers, said partition being apertured by a slot rabbeted at its lower edge, an inverted bag suspended in the upper chamber by its closed upper end and having its mouth extending into the slot in the partition, a bag mouth frame comprising complementary 115 wire rods, each having one end offset to afford a bent end adapted to lie in the rabbeted end of the slot in the partition, the rods being so arranged that their respective end bends lie in the rabbets at opposite ends of the slot, and means secured to the lower face of the partition to clamp the bag mouth and its associated frame in the rabbet. 120

2. In a dust arrester, a bag, upper and lower frames for holding the same in position, one of said frames being spring supported, together with a self-contained vibratory impact member carried by said 125

spring-supported frame, and serving, upon actuation, to alternately stress and relieve the supporting springs.

3. In a dust arrester, a bag, upper and lower frames for holding the same in position, one of said frames being spring supported, together with a self-contained vibratory impact member carried by said spring-supported frame, and serving upon actuation to impart successive blows to the spring-supported frame.

4. In a dust arrester, a bag, upper and lower frames for holding the same in position, one of said frames being spring supported, together with a self-contained vibratory impact member carried by said spring-supported frame, and serving upon actuation to impart successive blows in opposite directions to the spring-supported frame.

5. In a dust arrester, a series of bags, a fixed frame holding said bags open at their lower ends, a spring-suspended frame supporting the closed upper ends of the bags and normally holding said bags taut, in combination with a reciprocating member carried by the spring suspended frame and adapted to impart hammer blows in opposite

directions to said spring-suspended frame, and thus to render the bag fabric alternately slack and taut to free dust particles 30 therefrom.

6. In a dust arrester, a series of bags, a fixed frame holding said bags open at their lower ends, a suspension frame engaging said bags at their closed upper ends, springs 35 supporting said suspension frame and normally stressed to hold the bags taut, and a self-contained pneumatic vibrator mounted on said frame and adapted to impart hammer blows in opposite directions to said 40 frame, and thus, in cooperation with the supporting springs, to cause the bags to become alternately slack and taut to free dust particles therefrom.

7. In a dust arrester, a casing, filter bags 45 within the casing, a floating suspension frame for the bags, together with a pneumatic vibrator carried by the frame, and a flexible pneumatic pressure hose entering the casing and connected to the vibrator. 50

In testimony whereof I have signed my name to this specification.

GEORGE C. FATSCHER.
